Jon-Michael Burbage(57) **CLAIM**

The ornamental design for a battery package, as shown and described.

DESCRIPTION

FIG. 1 is a front perspective view of the battery package, showing our new design;

FIG. 2 is a perspective view thereof;

FIG. 3 is an exploded view thereof;

FIG. 4 is a bottom exploded view thereof; and,

FIG. 5 is a top view thereof.

In the drawings, the broken lines are for the purpose of illustrating environment only that forms no part of the claimed design.
